UNITED STATES PATENT OFFICE.

RAMON BOVÉ, OF NEW YORK, N. Y.

HAIR-WAVING APPLIANCE.

Application filed October 17, 1922. Serial No. 595,077.

To all whom it may concern:

Be it known that I, RAMON BOVÉ, a subject of the King of Spain, residing at New York city, State of New York, have invented 5 certain new and useful Improvements in Hair-Waving Appliances, of which the following is a specification.

This invention is a hair-dressing device and has for its object the provision of a 10 simple and inexpensive mechanism by the use of which a permanent wave may be formed in the human hair. A particular object of the present invention is to provide means whereby the hair-engaging members 15 may be locked in a set position while forming the hair so that the wave produced in the hair will remain for a long period so that it will be practically permanent. The invention is illustrated in the accompanying 20 drawings and will be hereinafter fully set forth.

In the drawings—

Figure 1 is a view showing my improved device applied to strands of hair as it appears when in use;

Fig. 2 is a perspective view of the device removed from the hair;

Fig. 3 is a plan view showing the hair-engaging members open to receive the hair;

Fig. 4 is a plan view showing the hair-engaging members closed and in the position assumed when in use;

Fig. 5 is a bottom plan view of the same, and

Fig. 6 is a section on the line 6—6 of Fig. 2.

In carrying out my invention, I employ a plurality of hair-engaging members, each of which consists of a trough-like body 1 having its side edges serrated or provided with teeth 2. These trough-like hair-engaging members are provided with perforations 3 through their bottoms so as to permit a circulation of hot air or other forms of heat 40 through the hair which may be secured in the trough. Constructed to fit within each trough-like body 1 is an upper covering member 4 which is of similar shape and is provided with perforations 5 through its bottom. At one end, the covering member is formed with a hook 6 adapted to engage through an opening 7 in the adjacent end of the base member 1 and thereby hingedly connect the two members, as will be readily un-

derstood upon reference to Fig. 6. At the 55 opposite end of the upper covering member, I secure a spring latch 8 which is adapted to pass through a notch 9 formed in the end of the base member and engage against the under side of the said member so as to hold 60 the two members in closed relation to clamp the hair between them. Each set or series of hair-engaging devices may include any desired number of units and to the under side of each unit or base member 1, I pivotally 65 attach one end of a link 10 whereby the units are held together but may have relative movement. By referring to Fig. 5 more particularly, it will be noted that the links are pivoted at fixed points to the alternate members and to the intervening members they are connected by pin and slot connections, as shown at 11. This pin and slot arrangement will permit the relative endwise movement 70 of the units to be varied within the limits 75 permitted by the slots so that waves of greater or less length may be formed in the hair according to individual preferences. I also pivotally attach to the under side of each end unit of each series or set, posts 12, 80 one of which posts has secured to or formed integral therewith a locking pin 13 which is adapted to pass through a diametrical opening formed through the other post, as shown in Fig. 6, and in the latter post is 85 mounted a binding screw 14 which is adapted to bear upon the pin and secure the same rigidly in the post so that the several units will be locked in the position in which they may be set.

In using the apparatus, the upper or covering members 4 of the several units are swung to open position, as shown in Fig. 3, and the units are all arranged in extended spaced relation, as shown in said figure, the link connections between the units serving to hold them parallel, as shown. The device is placed in position upon the head of the person whose hair is to be treated and so much of the hair as may be accommodated by the units is placed over the base members of the same. The upper members are then brought down over the hair and will be held in the closed position by the action of the several latches 8 in an obvious manner. The units are then given relative endwise movement in opposite directions so as to assume the positions shown

in Figs. 1, 4 and 5, the binding screw 14 being then turned home so that the parts will be locked in the position illustrated. As the several units are given relative end-
wise movement, they will be caused to move toward each other longitudinally of the series or set through the action of the links 10 and the hair engaged by the several units will be, consequently, moved first to one side and then to the other side so that waves will be formed therein. Heat is then applied to the device by the application of wet cloths or in any other preferred manner or the hair may be moistened somewhat before being engaged in the several units and then dry heat applied by the application of an air blast or otherwise. The perforations through the several members permit the heat to circulate through the hair and when the excess moisture has been driven from the hair, the device may be removed, whereupon it will be found that the hair has assumed a waved or curled form which will remain fixed for a long period and will not be entirely lost unless the hair be repeatedly combed or brushed in such a manner as to positively return it to a straight condition.

My device is very simple in its construction and efficient in operation. It may be easily manipulated and, as it is constructed of light metal, it will not be uncomfortable when in use, and inasmuch as the hair is engaged between two clamping members, it is protected against the direct action of excessive heat so that it is not relieved of all natural moisture and rendered brittle.

Having thus described the invention, what is claimed as new is:

1. A hair-waving device comprising a plurality of hair-clamping members, link connections between the several members whereby they may have movement toward or from each other lengthwise of the series and may also have relative endwise movement transversely of the series, and means carried by the under sides of the said members to lock them in a set position. 40

2. A hair-waving device comprising a plurality of hair-engaging units arranged in series, links connecting adjacent members of the series, said links being pivoted at fixed points on alternate units and having slots in their free ends, studs on the intermediate units each engaged by the slotted ends of two links, and means mounted on the under sides of some of the units for locking the series of units in a set position. 50

3. A hair-waving device comprising a set of hair-engaging units, link connections between the several units whereby they may have relative movement toward and from each other lengthwise of the set and also for relative endwise movement transversely of the set, posts pivotally mounted on the under sides of some of the units, a locking pin carried by one of said posts and extending through the other post, and means carried by the latter post for locking the pin therein. 60

In testimony whereof I affix my signature.

RAMON BOVÉ [L.S.]
